(57) **CLAIM**

We claim the ornamental design for a light fixture, as shown and described.

DESCRIPTION

FIG. 1 is a perspective view of a light fixture showing our new design.

FIG. 2 is a front view of the light fixture shown in FIG. 1.

FIG. 3 is a rear view of the light fixture shown in FIG. 1.

FIG. 4 is a first side view of the light fixture shown in FIG. 1.

FIG. 5 is a second side view of the light fixture shown in FIG. 1.

FIG. 6 is a plan view of the light fixture shown in FIG. 1; and,

FIG. 7 is a bottom view of the light fixture shown in FIG. 1. The bottom view forms no part of the claimed design. In the drawings, the broken lines depict environmental subject matter only and form no part of the claimed design. The dot and dashed lines define the bounds of the claimed design and form no part thereof
